ADDISON ALGER COE, OF BROOKLYN, NEW YORK.

SHELL-FISH DREDGER.

1,283,080.

Specification of Letters Patent. Patented Oct. 29, 1918.

Application filed February 25, 1918. Serial No. 218,925.

To all whom it may concern: -

Be it known that I, ADDISON ALGER COE, a citizen of the United States, and a resident of Brooklyn, county of Kings, and State of New York, have invented certain new and useful Improvements in Shell-Fish Dredgers, set forth in the following specification.

This invention relates to shell-fish dredgers.

10 Many species of shell-fish such as the clam family, including skimmers and mussels, are usually located several inches below the ocean bed and under a considerable depth of water, many times in abundance in water 15 over twenty feet deep. Heretofore it has been the practice to dredge these shell-fish with a pair of swiveled tongs, each tong having a long handle. When the handles were opened out, the tongs were opened. By forcing 20 the handles downward and inwardly, the tongs would be forced beneath the sand and together to grasp whatever shell-fish might be engaged therebetween. It was then necessary to lift up the tongs by the handles in 25 either hand and dump the catch in a boat, if there was any catch, an empty haul being not infrequent. With this practice, the necessary spread at the top of the handles to completely open the tongs has prevented satisfactory dredging in water deeper than about 30 ten feet.

An object of the present invention is to make possible and convenient shell-fish dredging in water of relatively great depth, 35 say at least twenty-five feet, and also to increase the speed and ease with which such dredging may be accomplished under water of any depth.

In the furtherance of these general objects, I propose to adapt a dredging mechanism to operation through the medium of a single handle. I further propose to facilitate the driving of tongs into the ocean bed by means of other than brute force, specifically through the medium of repeated blows 45 of a single handle acting like a ram or pile driver.

I further propose to facilitate the entrance and closing together of dredging tongs into 50 and beneath the ocean bed by coördinating the shape and movement of the tongs.

The above and further details of my invention will better be understood by reference to the illustrative embodiment described in the following specification in connection with the accompanying illustrative

drawings, which form a part hereof, in which like characters designate corresponding parts in the several figures, and in which—

60 Figure 1 is an elevation, partly in diagram and with parts broken away, of an embodiment of my invention;

Fig. 2 is a vertical section, with parts shown in elevation and parts broken away, 65 taken at right angles to the view in Fig. 1;

Fig. 3 is a fragmentary horizontal section, drawn to an enlarged scale through line III—III of Fig. 1;

Fig. 4 is a left-hand side elevation of the 70 structure shown in Fig. 1;

Fig. 5 is an elevation, drawn to a reduced scale, of the apparatus from the side viewed in Fig. 1, but with the mechanism in position to discharge the catch; and

75 Fig. 6 is a fragmentary view corresponding to Fig. 1, showing a modification.

A foot 1, preferably comprising a metal plate of considerable width, mounts a non-circular upright stem 2, conveniently fabricated of steel-stock, which may be secured to the foot 1 as by riveting. The stem 2 is provided with a fixed enlargement 3 at its upper end, preferably shaped and of a size to fit as a guide within the tubular ram 4, the bottom of which is closed with a cap or other suitable fixed closure 5, having a guiding perforation having a non-circular contour, like the stem 2. Thus the ram 4 may move up along the stem 2 until the enlargement 3 80 engages the head 5 and may move down on the stem 2 until the cap 5 strikes the toggle-head 6, preferably of tubular construction, having a top closure 7 slidable upon the stem 2 and a bottom closure 8 slidable upon the stem 2. Pivoted in suitable trunnions 9 and 9^a are two sets of toggle-arms 10 and 10^a, 85 operatively linking the arcuate tongs 11 and 11^a with the toggle-head 6. The tongs 11 and 11^a have sets of inwardly extending radius arms 12 and 12^a respectively, the inner ends of which are hinged by hinges 13 and 13^a to the foot 1 at approximately the center 90 of curvature of the arcuate tongs 11 and 11^a, so that, when the tongs pivot upon these hinges the tines move in a circular path corresponding substantially to their contour, and further in consequence displace nothing more than their own bulk or, in other words, do not sweep laterally through the ocean bed but merely penetrate, although, on account of their circular movement, their ends

come together as shown by the dot and dash lines in Fig. 1 and by full lines in Fig. 5.

The ram 4 preferably has threads 14 at its top end to secure the threaded coupling 15, anchored to a handle 16 of suitable length. The upper end of the handle preferably has a perforation 17 to secure the knotted end 18 of a cord 19, the bottom end of which is secured to the head 6 in a suitable manner, as by the lug 20, which serves as means for lifting the head 6 independently of the foot 1 and stem 2.

Of an extent preferably to extend out beyond the tongs 11 and 11^a, are suitably fixed 15 to the stem 2 on swivels two connecting links 22 and 22^a, the outer ends of which are hinged by pins 23 and 23^a to a catch basket B. The position of the pins 23 and 23^a is 20 preferably to the right of its gravity axis, as viewed in Fig. 1 and flexible links 24 and 24^a are connected between the frame of the basket and intermediate points on the links 22 and 22^a, so as to hold the basket B in a horizontal position when suspended, as 25 shown in Fig. 5.

It should be noted that the toggle-arms 10 and 10^a are shown having three legs b, c and d. This is a preferred construction when the tongs are of considerable size, although 30 it is of course to be understood that the legs b and d alone would be useful and satisfactory in some instances, and for small sizes of tongs that a single central leg c might be sufficient.

35 For operation, all that is necessary is to lower the dredger through the water until the foot 1 rests upon the ocean bed. A few blows of the ram 4, operated by an up-and-down movement of the single handle 16 causes the toggle-head 6 to impart the force 40 of the blows through the toggle-arms 10 and 10^a to the tongs 11 and 11^a, which are forced to swivel on their hinges, so that the points of the tines follow the paths shown in Fig. 1 45 through the sand to envelop any shell-fish, such as indicated by e between the tines. When the tongs have been forced home all that is then necessary is to lift the single handle 16 which, by the cap 5 engaging the 50 enlargement 3, lifts the stem 2 and with it the foot 1. The radius arms 12 and 12^a engaging the hinge pins 13 and 13^a cannot rotate downwardly any farther and the component of forces upon the arcuate tongs due to 55 the clasped sand and shell-fish is such as not to tend to open the tongs. The catch is therefore lifted out of the sand, the sand flows through the tines. The links 22 and 22^a relatively guide the dredger mechanism 60 and the basket into relative positions shown in Fig. 5. A pull upon the cord 19 then lifts the head 6 independently of the stem 2, which lifting through the operation of the toggle arms 10 and 10^a opens the tongs to 65 drop the catch into the basket B, which at

this time is pendant or resting upon the ocean bed beneath the dredger. During this operation it is very easy to determine how nearly full the basket B has become by the increase in weight after the mechanism has 70 been swiveled upwardly on the links 22 and 22^a. It is therefore not necessary to remove the dredger from the ocean bed until the basket B has been completely filled. The handle 16, therefore, for the most part acts 75 merely as an operator of the dredging mechanism. Furthermore, as but one handle is employed and there is no necessity of having wide-spreading parts, the only practical limit to the depth at which my dredger may 80 be employed is the limit imposed by the total weight of apparatus necessary to reach the desired depth.

In Fig. 6, I have shown a central tong 30, the tines of which project centrally straight 85 downwardly from a cross-bar 31. With such a structure, it is conceivable that either one or the other of the arcuate tongs 11 or 11^a might be eliminated, together with its operating mechanism, and the remaining 90 arcuate tong be employed to coöperate with the stationary downwardly projecting tong 30 to produce a mechanism of half the capacity of my preferred form. I show this modification for the purpose of eliminating 95 the possibility of an infringement of my rights by any such adaptation, which I consider to be covered by my claims, although I have expressed therein a pair of tongs. I naturally contemplate a single movable tong 100 coöperating with a stationary tong.

What I claim and what I desire to secure by United States Letters Patent is:—

1. A shell-fish dredger comprising a pair of hinged sand penetrating tongs; and 105 means for positively forcing said tongs downward and together at their tips comprising only one upwardly extending operating handle, rigid connecting arms between said tongs and said handle and a slack connection between said arms and handle so that said handle may deliver blows to operate said arms.

2. A shell-fish dredger comprising a foot adapted to rest upon the ocean bed; a pair 115 of tongs hinged relatively to said foot; a toggle-head; toggle-arms operatively connecting said toggle-head with said tongs and means for effecting a downward movement of said toggle-head to force said tongs 120 into said bed, comprising a vertically guided ram for delivering blows to said toggle-head.

3. In a shell-fish dredger a relatively stationary foot and vertical guide-stem; a pair 125 of tongs hinged relatively thereto; and a vertically movable ram guided by said stem for progressively operating said tongs by a series of blows.

4. A shell-fish dredger comprising a foot; 130

- a non-circular guide-stem extending upwardly from said foot and having an enlargement at its top; a toggle-head movably guided by said stem; a pair of tongs hinged 5 to said foot; toggle-arms operatively connecting said tongs and said head; a tubular ram for striking blows upon said head having a closure at its lower end fitting said non-circular stem to prevent relative rotation and inclosing said enlargement; and means for lifting said head independently of said foot.
5. In combination, shell-fish dredging mechanism comprising operating tongs and 10 means for lowering and raising said tongs upon and from the shell-fish bed; a catch basket; a pair of parallel arms hinged at one end to said mechanism and at the other end to said basket, whereby a lowering of 15 said mechanism causes a lateral separation of said mechanism and basket and a raising of said mechanism causes a superposed positioning of said mechanism relatively to said basket.
- 20 6. In a shell-fish dredger, a guide-stem having a foot adapted to rest upon the sur-
- face of a shell-fish bed; a pair of tongs hinged to said stem and having a closing movement beneath said foot; toggle mechanism having a head guided on said stem 30 and arms for operating said tongs; an operating rod free to move relatively to said stem and operable as a ram to force down by blows said toggle head to close said tongs when said foot remains stationary. 35
7. In a shell-fish dredger, a guide-stem having a foot adapted to rest upon the surface of a shell-fish bed; a pair of tongs hinged to said stem and having a closing movement beneath said foot; toggle mechanism having a head guided on said stem 40 and arms for operating said tongs; an operating rod free to move relatively to said stem and operable as a ram to force down by blows said toggle head to close said 45 tongs when said foot remains stationary; and means for lifting said stem independently of said rod.

In testimony whereof I have signed my name to this specification, this 23rd day of 50 February, 1918.
